FLASHLIGHT LENS RING

Herman G. Graubner, 765 Riverside Drive,
New York, N.Y.

Filed Nov. 27, 1959, Ser. No. 58,470

Term of patent 14 years

(Cl. D48—24)

Fig. 4

Fig. 1

Fig. 2

Fig. 3

Fig. 1 is an elevational view of a flash light lens ring embodying my design;

Fig. 2 is a plan view of the flashlight lens ring as seen from the top of Fig. 1;

Fig. 3 is a plan view of the flashlight lens ring as seen from the bottom of Fig. 1; and

Fig. 4 is a sectional view taken along the lines 4—4 of Fig. 1.

I claim:

The ornamental design for a flashlight lens ring, as shown.
